Thos. S. Sprague

UNITED STATES PATENT OFFICE.

AUGUSTUS DAY, OF DETROIT, MICHIGAN.

IMPROVEMENT IN BUTTON-HOLE CUTTERS.

Specification forming part of Letters Patent No. 135,893, dated February 18, 1873.

To all whom it may concern:

Be it known that I, AUGUSTUS DAY, of Detroit, in the county of Wayne and State of Michigan, have invented a new and useful Improvement in Button-Hole Cutters; and I do declare that the following is a true and accurate description thereof, reference being had to the accompanying drawing and to the letters of reference marked thereon, and being a part of this specification, in which—

Figure 1 is a perspective view with the blade extended; and Fig. 2 is a plan with the blade closed.

Like letters refer to like parts in each figure.

The nature of this invention relates to the construction of a device for cutting button-holes in fabrics; and it consists of a metallic plate, the two sides of which are turned over to form guides in which a steel cutter slides, as hereinafter set forth.

In the drawing, A represents a rectangular piece of metal, the two sides of which are turned over to form the guides a; an oblong slot b is cut longitudinally through the plate A. B is the blade, made from a rectangular piece of steel, one end of which is cut away at a long bevel, thus forming the cutting-edge c. This blade is of sufficient width to slide freely in the guides a; and near the base of the blade

is cut or punched a hole, d. The slot b, in the plate A, and the hole d, in the blade B, are for the purpose of enabling the user of the device to more easily adjust the blade than if they were both solid.

To use this cutter take it in the right hand, and with the thumb of the left push the blade out of the case to the size of the button to be used. Hold the cloth in the left hand between the first and second and thumb and third fingers. Take the cutter in the right hand between the thumb and fingers, with the edge toward the right hand; start from the point where you wish to cut: push down through the cloth to the end of the case.

Should the blade become loosened in the case so as to move too easy hammer down the flange or guide at the back of the cutter.

The blade should be pushed back in the case when not in use.

What I claim as my invention, and desire to secure by Letters Patent, is—

The case A, having the slot b, in combination with knife B, having the opening d, as described.

AUGUSTUS DAY.
